UNITED STATES PATENT OFFICE.

HARRY G. JENNISON, OF TOLEDO, OHIO.

BLOCK PAVEMENT.

1,340,896.

Specification of Letters Patent. Patented May 25, 1920.

Application filed March 7, 1917. Serial No. 152,970.

To all whom it may concern:

Be it known that I, HARRY G. JENNISON, a citizen of the United States of America, residing at Toledo, Lucas county, Ohio, have 5 invented new and useful Block Pavements, of which the following is a specification.

This invention relates to block pavements and means for initially spacing the blocks.

This invention has utility when incorporated in wood block pavement more particularly in the provision on a block of yieldable spacing means susceptible to distortion in responding to block disturbance, as weathering.

15 Referring to the drawings:

Figure 1 is a perspective view of a multiple length block section or plank of the cross-sectional area desired to have for the block;

20 Fig. 2 is a similar view of such section with the continuous seats or grooved means formed therein;

25 Fig. 3 is a perspective view of this multiple length block section with the spacing means seated in the grooves;

Fig. 4 is a perspective view of a block cut from the multiple length section with its spacing means assembled therewith as a unit;

30 Fig. 5 is a perspective view of a pavement section, say for street work embodying the blocks of Fig. 4 as assembled; and

Fig. 6 is a perspective view of the wood block pavement as developing in use showing the action of the spacing means in crushing down as adapting to block changes.

In the laying of pavement, it is natural in order to line-up the blocks that they should be placed in contacting relation not only to 40 preserve the staggering but the general pavement lines. Such setting for wood blocks is objectionable even with the impregnation say with waterproofing substances for temperature and weather conditions enter to 45 disturb cross-sectional area of the block notwithstanding the block may maintain a thoroughly aseptic condition.

The invention herein takes into account the desirability of placing the blocks into 50 abutting relation but automatically provides a spacing between the blocks. In this spacing there is a projection from one block operating as a means for determining a spaced relation between it and the adjoining 55 block but such spacing provision is of a nature and extent distinguishing from a posi-

tive permanent holding of the blocks in such spaced relation.

In the carrying out of the invention herein, the plank 1 of cross-sectional area desired for the blocks, such plank being of multiple block length, has formed therein throughout its length the seats 2 lengthwise of the grain of the wood which seats 2 may have their anchoring more effective in giving 60 some undercut, the showing being dove-tail. Inserted or formed in this groove is the spacer 3 preferably of a semi-fluid composition or plastic binder.

This spacer formed in a groove or grooves 70 throughout their length is of small contacting region at its exposed edge and the spacer is in its nature crushable or yieldable under load strain but of sufficient toughness and permanence for permitting the handling in 75 shipment and laying. In its nature it is somewhat of an elastic mastic.

From this continuous length or multiple block section with the spacer therein are cut the blocks 4 of a length along the plank to 80 bring them to a height of block desired with the wear face of the block across the grain of the wood, or with the grain of the wood running away from the wear face. This completed block 4 with the spacing means 3 85 is of a form for ready aseptic treatment, impregnation or waterproofing as desired say with a hydro-carbon.

This block 3 is assembled in staggered relation in the pavement with its spacing 90 means coacting with the adjacent blocks on the sides where the spacing means are absent. In some instances the narrow way spacing means of the blocks may be dispensed with and the terminal spacing means only used 95 for the block distortion due to weathering is more in this direction of the block when the age rings of the blocks approximate this direction.

As the pavement is installed with these 100 crushable edges of the spacing means 3 abutting adjacent blocks the use and weathering conditions act upon the blocks in tending to work the blocks into closer relation. This is permitted by the lugs or spacing means 3 105 running away from the pavement surface notwithstanding the interstices between the blocks may be brushed in or filled with a filler say of sand and a hydro-carbon with sufficient hydro-carbon to flux the sand under compression strains. Accordingly, the 110 blocks of the pavement remain placed, the

seatings in the blocks introduce no weakness for even in the event of moisture attempted attacks the grooves are bottomless to allow the moisture to pass down the grooves as readily as down the block side. In the compression movement the small contact edges of the spacing means 3 as to relative greater side area of the blocks may give way more or less to produce the means 5. The preparation 10 of the plank to provide the spacing means, while removing some of the wood to form a seat, does not detract from the cross-sectional area of the plank to be used in the pavement, while the addition to the plank of the spacing means really increases the cross-sectional area and accordingly is a factor in reducing lumber expense.

What is claimed and it is desired to secure by Letters Patent is:

20. 1. A pavement comprising transverse rows of rectangular grain up wood blocks, the blocks of one row breaking joints with the blocks of an adjoining row, said blocks being spaced at the joints between the blocks 25 of a row, in effecting said spacing there being a groove in one block extending in the direction of the grain of such block through the pavement, a compressible strip in said groove projecting out of said block toward

the adjacent block, said strip extending from 30 the pavement face to the base of the pavement, and a yieldable filler in said joint co-acting with the projecting spacing strip in allowing the spaced blocks of the pavement to vary the spacing distance therebetween 35 by crowding into such space.

2. A pavement comprising wood blocks of a contour normally to permit close laying thereof, one of said blocks having along a vertical side thereof a groove extending 40 from the pavement top to the pavement base in the direction of the grain of the wood of the block, and a spacing element dovetailed in said groove and having a narrow compressible edge projecting therefrom to position the vertical face of the adjacent block initially in spaced relation from the block mounting the element.

3. A paving block of rectangular formation, a groove or grooves formed in vertical 50 relation in one or more of the side faces of said block, means fitted in the said groove or grooves for spacing the said blocks apart when regularly placed together, as and for the purpose specified.

In witness whereof I affix my signature.

HARRY G. JENNISON.
